UNITED STATES PATENT OFFICE.

PETER R. THOM, OF APPLETON, WISCONSIN, ASSIGNOR TO VALLEY IRON WORKS COMPANY, OF APPLETON, WISCONSIN, A CORPORATION OF WISCONSIN.

BEATING-ENGINE.

1,229,545.

Specification of Letters Patent. Patented June 12, 1917.

Application filed March 16, 1916. Serial No. 84,551.

To all whom it may concern:

Be it known that I, PETER R. THOM, a citizen of the United States, and resident of Appleton, in the county of Outagamie and 5 State of Wisconsin, have invented new and useful Improvements in Beating-Engines, of which the following is a description, reference being had to the accompanying drawings, which are a part of this specification.

10 The invention relates to improvements in beating engines.

In the paper making art the half or coarse pulp or other material is passed through a beating engine to be shredded or reduced 15 to a finer pulp and in being worked, the material or stock is mixed with water to form a semi-liquid mass which is ordinarily contained within a centrally partitioned oval-shaped vat provided with a rotary reducing member which extends transversely 20 of a portion of the vat on one side of the partition. The stock is caused to flow between the rotary reducing member and a co-acting knife member positioned below the 25 reducing member. The reducing member is in the form of a drum having projecting and longitudinally extending knives or blades which coact with the knife member in macerating or reducing the material. In 30 order to cause a positive circulation of the pulp around the vat on each side of the partition a positive feed of the pulp to the reducing member, the vat adjacent to the knife member is provided with a front and 35 back fall which gives the desired feed and circulation.

The rotary reducing member macerates the pulp material and moves it over the back fall and in thus moving the pulp material 40 has a tendency to stick and is carried around by the rotary member thus causing the pulp to pack and clog into the spaces between the knives and around the member. This packing of the material interferes with the 45 macerating work of the reducing means and increases the power required for operating the machine, and is objectionable in many other ways.

It is one of the objects of the present invention to obviate the before mentioned objectionable features and provide a beating engine with means for stripping the greater portion of the pulp material from the rotary member which has passed between the 55 reducing means, and to direct said material

over the backfall to increase the circulation of the pulp in the vat.

A further object of the invention is to provide a beating engine which is of simple construction, is strong and durable and is 60 well adapted for the purpose described.

With the above and other objects in view, the invention consists of the improved beating engine and its parts and combinations as set forth in the claims, and all equivalents thereof.

In the accompanying drawing in which the same reference characters indicate the same parts in all of the views;

Figure 1 is a top view of a portion of the 70 improved beating engine, parts broken away to show the interior construction;

Fig. 2 is a longitudinal sectional view thereof taken on line 2—2 of Fig. 1.

Referring to the drawing, the numeral 5 75 indicates an oval-shaped vat which comprises the bottom portion 6, the side wall 7 and the longitudinally extending medial partition 8. A rotary knife drum or reducing member 9 mounted on a transversely 80 extending shaft 10 is positioned to rotate in one of the troughs 11 formed by the medial partition 8, and its knives 12 co-act with the stationary knives 13 mounted on the bottom portion 6 of the vat immediately beneath the rotary member. An inclined bottom portion or front fall 14 leads up to the 85 stationary knives 13 and directs the pulp or stock thereto and an inclined dam or back fall 15 serves to assist in circulating the 90 pulp or stock around the vat. The front, or nearest face 16 of the back fall to the rotary member, is concaved and the rear face 17 is inclined downwardly from the apex in a straight line. The concave face 95 is curved on a radius whose axis is to the rear of the axis of the rotary member to form an upwardly flaring space between the rotary member and the back fall. A deflecting member 18 positioned within the 100 flaring space and extending transversely of the trough has its lower curved edge portion 19 positioned closely to the peripheral edge portions of the knives 12 near the bottom portion of the trough. This position of the 105 lower edge of the deflecting member deflects the pulp material away from the knives of the drum and into the space 20 between the deflecting member and the concaved face of the back fall. This 110

space also flares upwardly so that the pulp material being forced continually into the lower end will be easily pushed upwardly in the flaring space and will drop over the apex of the back fall and slide down the rear inclined face thereof and thus cause the pulp material to circulate around the trough of the vat.

10 The pulp material in engaging the lower edge of the deflecting member will, to a large extent, be withdrawn from the spaces between the knives and hub comparatively a small amount of pulp will be carried around and over the rotary member thus 15 lessening the power required to drive the engine and providing a more evenly macerated stock.

10 A cover 21 of ordinary construction is provided for the rotary member and the 20 back fall of the engine.

From the foregoing description it will be seen that the improved beating engine is of very simple construction and well adapted for the purpose described.

25 What I claim as my invention is:—

1. A beating engine, comprising a vat provided with a stationary reducing member and a back fall, a rotary member positioned above the reducing member and adjacent to the back fall, and a deflecting member interposed between the back fall and the 30 rotary member for deflecting material from said rotary member toward the back fall.

2. A beating engine, comprising a vat provided with a stationary reducing member and a back fall, a rotary member positioned above the reducing member and adjacent to the back fall, and a deflecting member extending transversely of the vat and located between the rotary member and the 40 back fall and having its lower edge portion positioned close to the periphery of the rotary member.

3. A beating engine, comprising a vat provided with a stationary reducing member and a back fall, a rotary member positioned above the reducing member and adjacent to the back fall, and a deflecting mem-

ber extending transversely of the vat and located between the rotary member and the 50 back fall and having a lower curved portion the lower edge of which is positioned close to the periphery of the rotary member to deflect pulp material therefrom into the space between the deflecting member and 55 the back fall.

4. A beating engine, comprising a vat, a fixed pulp reducing member located in the lower portion of the vat, a back fall located in the vat and having a concave face adjacent the reducing member, a drum mounted in the vat and having longitudinally extending blades which co-act with the fixed reducing member in macerating material passing therebetween, and a deflecting member positioned between the drum and the back fall and extending downwardly at an angle toward the lower portion of the drum and having its lower edge portion adjacent the drum blades to deflect material therefrom 70 between the deflecting member and the backfall.

5. A beating engine, comprising a vat, a fixed pulp reducing member located in the lower portion of the vat, a back fall located 75 in the vat and having a concave face adjacent the reducing member, a drum mounted in the vat and having longitudinally extending blades which co-act with the fixed reducing member in macerating material passing 80 therebetween, and a deflecting member positioned between the drum and the back fall and extending downwardly at an angle toward the lower portion of the drum and having a lower portion which curves toward the drum and the lower edge portion thereof positioned close to the drum blades 85 to deflect material therefrom between the deflecting member and the back fall.

In testimony whereof, I affix my signature, 90 in presence of two witnesses,

PETER R. THOM.

Witnesses:

M. McMAHON,
M. TIETZ.
